SASH LOCK

Eugene Ora Daniels, Toledo, Ohio

Application August 26, 1939, Serial No. 292,149

2 Claims. (Cl. 292—288)

This invention relates to improvements in window sash locks, and an object of the invention is to provide a lock of this character which may be readily mounted in the groove for the lower window sash and will serve effectively when so positioned for securing both the upper and lower sashes against being opened beyond a predetermined amount to the end that either or both sashes may be raised to the desired position for 10 ventilating purposes without danger of an unauthorized person entering a house or room through the window.

The invention together with its objects and advantages will be best understood from a study of 15 the following description taken in connection with the accompanying drawings wherein:

Figure 1 is a perspective view illustrating the application of the invention.

Figure 2 is a longitudinal sectional view taken 20 through a window structure further illustrating the application of the invention and with both sashes in an open position and secured thereby through the medium of my improved sash lock.

Figure 3 is a perspective view of the sash lock. 25 Figure 4 is a perspective view of the stationary body plate or member, and

Figure 5 is a similar view of the sliding body plate or member forming part of the lock.

Referring more in detail to the drawings it 30 will be seen that in the preferred embodiment thereof the improved sash lock comprises a pair of complementary body plates including a relatively stationary body plate 5 and a slideable body plate 6.

The body plate 5 is provided at opposite side edges thereof with integral guide channels 7 which accommodate the side edges of the sliding plate 6.

Plate 5 is also provided at opposite side edges 40 thereof with integral clamping jaws 8 that complement clamping jaws 9 provided at opposite side edges of the plate 6, jaws 8 being adapted to engage the outer face of the stop strip 10 while the jaws 9 are adapted to engage the inner face of the parting strip 10' so as to hold the device extending across a groove for the lower sash. To accommodate the jaws 9 plate 5 is notched as at 11.

For shifting the plate 6 relative to the plate 5, 50 and for securing the plates 5 and 6 at the desired position of adjustment, there is provided an adjusting screw 12 which at the head-equipped end 13 thereof is rotatably accommodated within an opening 14 provided therefor in a flange 15 provided at one end edge of the plate 5. At said

head-equipped end 13 the screw 12 is provided with a removable collar 16 that is disposed on the shank of the screw at the side of the flange 15 opposite to the head 13 so as to coact with the head for holding the screw properly engaged in the opening 14 for rotative movement of the screw, at the same time holding the screw against longitudinal movement through the opening 14.

The threaded shank portion of the screw 12 has threaded engagement with the threaded opening in a boss 17 formed integral on the plate 6 at one end edge of the plate. Thus it will be seen that by turning the screw 12 in the proper direction plate 6 may be projected or retracted relative to the plate 5 for moving the 15 jaws 9 toward and away from the jaws 8 for clamping the lock in position extending across the groove for the lower sash or for releasing the lock for removal from said groove.

Pivotedly mounted on the plate 6 are a pair 20 of complementary sash-engaging and locking jaws 18—18. Adjacent one end thereof the jaws 18 have overlapping portions that are apertured and accommodate a pivot bolt 19. At said end the jaws 18 are also provided with angular extensions 25 20 that serve as finger pieces or handles for manually manipulating the jaws.

At the opposite ends thereof the jaws 18 are provided with angular cutting edges 21 provided for biting engagement with the frame of the 30 upper sliding sash 22 to secure the same against sliding movement.

At the tooth-equipped ends 21 thereof the jaws 18 are suitably provided as at 23 for the anchoring thereto of the ends of a coil spring 24 that 35 normally act to urge the ends 21 of the jaws towards one another. Movement of the ends 21 of the jaws towards one another in response to the action of spring 24 is limited through the medium of a stop 25 struck out from the plate 40 6 as shown.

The device is placed in one of the grooves for the lower sash and in a position where it is desired to stop upward movement of the upper end of said lower sash. The head 13 of the screw 45 12 is turned to cause the jaws 8 of plate 5 to engage the outer face of the stop strip 10 and the jaws 9 to engage the inner face of the parting strip 10' so as to hold the device extending across the groove between said strips and while the 50 screw is being turned the members 18 are held in spread apart position so that their ends 21 do not project beyond the adjacent end of the plate 6 and will, therefore not engage the upper sash. After the device is put in position these members 5

18 are released so that their ends 21 will engage parts of the upper sash.

Thus the lower sash can only be raised to a position where its upper end will engage the device and the upper sash, if partly open, cannot be raised or lowered as the ends 21 of the members 18 will prevent movement in either direction of the upper sash for when the sash is moved in one direction one of the points 21 will dig 10 into the frame member of the sash and when moved in an opposite direction the other pointed member 21 will dig into the sash.

Having thus described the invention what is claimed as new is:

15. 1. A sash lock comprising a pair of plates one 15 slidable on the other, a pair of jaw members on each plate for engaging side walls of a groove bridged by the plates, a screw rotatably carried by one plate and the other plate having a threaded 20 hole therein for receiving the screw, said screw when turned moving one plate relative to the other, guides on one plate receiving portions of the other plate, a stud carried by one plate, a pair of elongated members having overlapping 25 intermediate portions pivotally supported by said stud, finger engaging parts on the inner ends of said elongated members, the other ends of said members having cutting edges thereon and said other ends normally projecting from the adja-

cent end of the stud carrying plate but said ends moving inwardly of said edge when the elongated members are spread apart at their outer ends and spring means for normally holding the said outer ends adjacent each other.

2. A sash lock comprising a first plate having guideways on its side edges and a flange at one end and jaw members at its side edges adjacent said one end, said jaw members extending in a direction opposite to the flange, a second plate 10 slidably arranged on the first plate and having its side edges engaging the guides, a lug on the inner end of the second plate having a threaded hole therein, a screw rotatably supported by the flange and engaging the threaded hole, said second plate having jaws extending from its side edges, said jaws lying in planes which are inwardly of the planes of the first-mentioned jaws and the first plate having slots in its side portions placed inwardly of the guides for receiving the jaws of the second plate when the plates are moved toward each other and means carried by the second plate forming stop means for an upper sash, said plate being adapted to bridge a lower sash guide groove in the window frame 20 with the jaws of the two plates engaging side walls of the groove, whereby the plates form stop means for the lower sash.

EUGENE ORA DANIELS.
